Franklin Simon & Co., Inc., New York, N. Y.

Application January 16, 1936, Serial No. 60,609

Term of patent 3½ years

To all whom it may concern:

Be it known that I, Viola Mayer, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The elements between the dress lapels at the neckline, represent a vestee which has an opening beneath the ascot.

The elements on the yoke and pocket portions of the dress represent double folded inverted box-pleats which have their outer fold placed lower than their corresponding inner pleat.

I claim:

The ornamental design for a dress, substantially as shown and described.

VIOLA MAYER.
